US00D518265S

(12) **United States Design Patent** (10) **Patent No.:** **US D518,265 S**
(45) **Date of Patent:** **** Mar. 28, 2006**

(54) **LIQUID CONTAINER WITH LID**

(75) Inventors: **Gary F. Prokop**, Wheaton, IL (US);
Randall P. Bell, River Forest, IL (US);
Mark D. Kiel, Bensenville, IL (US)

(73) Assignee: **Valspar Sourcing, Inc.**, Minneapolis,
MN (US)

(**) Term: **14 Years**

(21) Appl. No.: **29/197,433**

(22) Filed: **Jan. 15, 2004**

(51) LOC (8) Cl. **07-07**

(52) U.S. Cl. **D32/53.1; D9/432**

(58) **Field of Classification Search** D32/53,
D32/53.1, 54; D3/273, 274, 282, 302; D7/601,
D7/602, 615, 629, 630; D9/424, 425, 430-432,
D9/435, 436; 220/254.1, 254.8, 600, 639,
220/645, 652, 660, 669, 674-679; 206/503,
206/508

See application file for complete search history.

(57) **CLAIM**

The ornamental design for a liquid container with lid, as shown and described.

DESCRIPTION

FIG. 1 is an upper perspective view of a liquid container with lid showing the new design;

FIG. 2 is a left side elevation view thereof;

FIG. 3 is a right side elevation view thereof;

FIG. 4 is a rear side elevation view thereof;

FIG. 5 is a front side elevation view thereof;

FIG. 6 is a top plan view thereof;

FIG. 7 is a bottom plan view thereof; and,

FIG. 8 is a lower perspective view thereof.

The features illustrated in broken lines in the figures do not form a part of the claimed invention.
